UNITED STATES PATENT OFFICE.

JOHN W. FARLEY, OF CLEVELAND, OHIO.

CEILING SLEEVE.

1,411,241.

Specification of Letters Patent. Patented Mar. 28, 1922.

Application filed August 22, 1921. Serial No. 494,201.

To all whom it may concern:

Be it known that I, JOHN W. FARLEY, a citizen of the United States, residing at Cleveland, in the county of Cuyahoga and State of Ohio, have invented certain new and useful Improvements in Ceiling Sleeves; and I do declare the following to be a full, clear, and exact description of the invention, such as will enable others skilled in the art 10 to which it appertains to make and use the same.

My invention relates to improvements in ceiling sleeves and has for its principal aim to improve upon the construction shown by U. S. Patent 1,060,328, issued April 29, 1913, 15 to myself, Matilda S. Farley and David F. Farley. While the patented device was an efficient article, it was usable only when the cellular asbestos pipe covering extended 20 throughout the length of the pipe, whereas the present invention aims to make novel provision for retaining a short length of pipe covering, passing only through the ceiling of one room and the floor of the room above. 25 With the foregoing in view, the invention resides in the novel subject matter hereinafter described and claimed, the descriptive matter being supplemented by the accompanying drawing.

Figure 1 is a side elevation partly in section showing a ceiling sleeve constructed in accordance with my invention, applied to a length of pipe and a cellular insulating covering for said pipe.

Figure 2 is a vertical sectional view cut longitudinally through the device.

Figure 3 is a horizontal sectional view as indicated by line 3—3 of Fig. 1.

Figure 4 is a fragmentary view similar to Figure 4 is a fragmentary view similar to 40 a portion of Fig. 2, but showing a slightly different form of construction.

In the drawing above briefly described, the numeral 1 designates a relatively short sleeve formed of sheet metal and split at one side 45 throughout its length, one edge of said sleeve having a slot 2, while the other edge is provided with a tongue 3 for reception in said slot. The lower end of the sleeve 1 is provided with an ornamental outwardly extending flange or collar 4 adapted to bear against the ceiling as shown in Fig. 2, this flange being preferably attached to the sleeve in the manner shown, that is, the inner edge of the collar is circumferentially split at spaced 50 points and bent upwardly and outwardly to

provide tongues 5, while the lower end of the sleeve is split also and bent horizontally inward to form tongues 6 which are received between the body of the collar and the tongues 5 of the latter, said tongues and body being by preference secured together by rivets or the like 7. Preferably, but not necessarily, the lower end portion of the sleeve 1 is formed with a continuous external bead 8.

The numeral 9 designates a relatively long sleeve whose lower end is adapted to receive the sleeve 1 as shown in Figs. 1 and 2, said sleeve 9 being split at one side throughout its length and having at its 70 edges an inter-fitting tongue and slot 10 and 11 respectively, said sleeve being held in contracted position by metal straps 12 such as those shown in the patent above referred to. The upper end of the sleeve 9 is split and 75 bent laterally outward to provide flanges 13 adapted to rest on the upper surface of the ceiling which is in most cases formed by the floor of the room above. The two sleeves 1 and 9 are telescoped with each other 80 around the usual or any preferred pipe covering C, said sleeves being relatively shifted according to the thickness of the material through which they must extend, and in order to properly support the lower 85 sleeve 1 in position with its flange or collar 4 resting against the ceiling, I provide a suspending wire 14 which may be round or flat as desired, the lower end of said wire having a hook 15 received in a slot 16 in the 90 upper end of the sleeve 1, while the upper end of said wire is adapted to be bent laterally as seen at 17 so as to hold it against descent and thereby similarly hold the sleeve 1. The bend 17 may take place directly over the flanges 13 as shown in Figs. 1 and 2, or said wire may first pass upwardly through an opening 18 in a collar 19 which surrounds the pipe 20 and extends outwardly over the flanged upper end of the 100 sleeve 9. This collar is used in both forms of my invention, but only in Fig. 4 have I illustrated the wire 14 extending through an opening 18 in said collar.

From the foregoing, taken in connection 105 with the accompanying drawing, it will be seen that I have provided an extremely simple and inexpensive, yet a highly efficient and desirable device for carrying out the objects of the invention; and since ex- 110

cellent results may be obtained from the details disclosed, they may well be followed. I wish it understood, however, that within the scope of the invention as claimed, numerous minor changes may be made.

I claim:

- 10 1. A ceiling sleeve comprising upper and lower split telescopedically engaged sections, each of which is provided with an outwardly extending flange, and a pliable non-resilient suspension wire extending upwardly from the lower sleeve section within the upper section and adapted to have its upper end bent laterally at the upper end of said upper section, to hold the lower section against descent.
- 15 2. A ceiling sleeve comprising upper and lower telescopedically engaged sleeve sections, both split throughout their lengths and having interfitting tongues and slots at their meeting edges, the upper end of said upper section and the lower end of the lower section being provided with an outstanding flange, straps passing around said upper section to hold the same in contracted position, and a suspending wire connected with the lower sleeve section and extending upwardly therefrom through the upper section, the

upper end of said wire being adapted to be laterally bent to hold it against descent. 30

3. A structure as specified in claim 1, said wire having a hook on its lower end, detachably engaged with a slot in the lower sleeve section.

4. A ceiling sleeve comprising upper and lower telescopic sections split throughout their length to permit them to be applied to a pipe after passage of the latter through a ceiling and floor, the ends of said sleeve having outstanding flanges to contact, respectively with the ceiling and floor above, a collar adapted to surround the pipe and to cover the upper end of the sleeve, said collar having an opening, and a suspending wire of pliable non-resilient nature, said wire being attached to the lower sleeve section, extending upwardly entirely through the upper sleeve section and through the opening in said collar, and having its upper end bent laterally upon the upper surface of said collar, whereby to support the lower sleeve section and to hold said collar in place.

In testimony whereof I have hereunto set my hand.

JOHN W. FARLEY.
